(57) **CLAIM**

The ornamental design for a packaging container as shown and described.

DESCRIPTION

FIG. 1 is a perspective view of a packaging container showing my design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof; and,

FIG. 7 is an exploded perspective view showing the state that the inner container is removed from the outer container. The broken lines depict portions of the packaging container that form no part of the claimed design.
